UNITED STATES PATENT OFFICE.

JOHN N. MACDONALD, OF HARTFORD, CONNECTICUT.

CHAIN-REPAIRING IMPLEMENT.

13,957.

Specification of Reissued Letters Patent. Reissued Aug. 3, 1915.

Original No. 965,722, dated July 26, 1910, Serial No. 507,659. Application for reissue filed June 25, 1912.
Serial No. 705,884.

To all whom it may concern:

Be it known that I, JOHN N. MACDONALD, a citizen of the United States, residing at Hartford, in the county of Hartford and 5 State of Connecticut, have invented new and useful Improvements in Chain-Repairing Implements, of which the following is a specification.

This invention relates to an improved implement for repairing chains, such as the tire chains of automobiles and the like, and it has for its object to provide a simple and improved device of this character, which may be conveniently carried in a tool chest 10 or in an ordinary repair kit and by the use of which links may be expanded and again closed as may be required.

Another object of the invention is to provide a simple and improved implement in 20 the shape of a pair of tongs or pliers and having jaws that are shaped to form coacting wedges which may be inserted in the joint of a chain link for the purpose of expanding the latter when the jaws are closed 25 together.

A still further object of the invention is to construct the jaws of the tongs or pliers with shoulders or off-sets upon which a chain link may be supported while being 30 compressed to close the joint.

A still further object of the invention is to so construct the shoulders or off-sets that they may be utilized for the purpose of compressing the ends of a chain link between them.

With these and other ends in view, which will readily appear as the nature of the invention is better understood, the same consists in an improved construction and a novel 40 arrangement and combination of parts which will be hereinafter fully described and particularly pointed out in the claims.

In the accompanying drawing has been 45 illustrated a simple and preferred form of the invention; it being however understood that no limitation is necessarily made to the precise structural details therein exhibited but that changes, alterations and modifications within the scope of the invention may 50 be resorted to when desired.

In the drawings: Figure 1 is a front view of an implement constructed in accordance with the invention. Fig. 2 is a side view of the same. Fig. 3 is a transverse sectional

view taken on the plane indicated by the 55 line 3—3 in Fig. 1. Fig. 4 is a transverse sectional view taken on the plane indicated by the line 4—4 in Fig. 1. Fig. 5 is a detailed front view showing the jaws of the implements in open position. 60

Corresponding parts in the several figures are denoted by like characters of reference.

The improved implement is composed of two members, A and B each comprising a handle portion 6 and a jaw portion 7. The 65 jaws 7 are formed of considerable width as compared with the handles, and said jaws are shaped to form curved or arcuate hooks, the bills of which, 8, extend toward each other; the bill of one hook being overlapped 70 by the bill of its mate. The members A and B are provided adjacent to the hook shaped jaws and intermediate said jaws and the handle portions, with laterally extending off-sets or shoulders 9, for the passage of the 75 connecting pin or pivot 10 which is eccentrically disposed near the outer edge of one of the shoulders 9 and at a point remote from the outer edge of the shoulder or off-set 9 of the proximate member so that the 80 outer face of one of the jaw-bills, and the inner face of the bill of the other jaw will be concentric with the axis of the pivot 10; said faces being also devised to lie in contact with each other when the jaws are 85 closed together. The bills 8 of the hook shaped jaws 7 are externally, somewhat wedge shaped as shown and owing to the eccentric disposition of the pivot connecting the members A and B the said bills will 90 move in contact with each other, while the jaws are being moved to an open position, causing the sharp edges of the bills to be adjacently placed when the jaws are opened, as will appear by reference to Fig. 5 of the 95 drawings. During the closing the external part 8¹ of the outer bill and the internal part 8² of the inner bill act as expanding faces in opposite directions.

The jaws are formed with lateral projections or off-sets 11 on their opposite faces, said off-sets combining with the bill portions of the jaws to form a recess of the shape and dimensions of an oblong chain link, of one of the kind that the tool is designed to operate upon; the outer portions of the jaws are relatively of great width and 105 by properly shaping the jaws they will when

closed together exert an expanding wedge action upon material, such as a chain link engaged thereby.

As shown in the drawings the outer wedge 5 surface 8^1 of the overlapping bill and the inner wedge surface 8^2 of the underlapping bill are substantially concentric curves or tangents to concentric curves so that as the bills pass each other these outer wedging 10 surfaces which engage the opposite faces of the hook or link remain substantially parallel. The center of the curves of the surfaces 8^1 and 8^2 is preferably a point spaced at about the same distance from the longitudinal 15 median line of the tool as is the pivot 10 but on the opposite side thereof. This brings the expanding faces 8^1 and 8^2 of the bills 8 substantially transverse to the median line when the tool is closed.

When a chain is to be disjointed for the purpose of inserting a new link or for any other reason, one of the links may be opened by swinging the jaws of the tool to an open position, after which the terminal edges of the jaws are placed in engagement with the joint of the link upon opposite sides of the latter; by closing the jaws together the wedge shaped bills of the jaws will spread the link open as will be readily understood.

If a link is to be closed, said link, if of the conventional oblong shape, may be placed between the jaws while the latter are open in such a manner as to be supported upon the off-sets 11 and between the latter and the bills of the hooks constituting the jaws; by closing the latter the link will be compressed as will be readily understood. Other forms of links may be closed by pressure between the portions of the jaws adjacent to the inner faces of the shoulders or off-sets 11, which latter will constitute stops to prevent slipping.

Having thus described the invention what is claimed is:

1. A tool of the class described comprising a pair of pivotally connected members having terminal jaws provided with bills overlapping one another in opening and closing, a pivot for said members set eccentric

to the respective inner and outer faces 50 of said bills, and stops formed on said jaws to limit the movement of said bills relative to each other, said bills having respectively outer and inner overlapping contacting faces concentric with said pivot throughout, 55 so as to move by and lie in contact with each other throughout their movement in passing one another.

2. A tool for opening and closing chain links, comprising a pair of crossed members pivoted together laterally of the longitudinal median line of the tool, and provided with wedge shaped bills having nearly opposed apices and similarly disposed adjacent free inner and outer expanding faces 60 arranged to overlap when closed, said faces formed upon curves substantially concentric to the pivot of the tool whereby said faces pass each other in substantially continuous contact and mutual support throughout the 70 closing movement of the jaws past each other to produce an equal opposite wedging action between the advancing outer expanding face of one of the bills and the inner portion of the inner expanding face of the 75 other bill effective to open the link without jamming the link upon the bills.

3. A tool for opening and closing chain links comprising a pair of pivotally connected members having jaws provided with 80 wedge shaped bills, said bills having respectively an inner and an outer expanding face and an outer and an inner face respectively, said last named faces traveling past each other in substantially continuous contact 85 and mutual support throughout the entire closing movement of the bills past each other whereby to produce a supported wedging action between the outer expanding face of one of the bills and the inner expanding 90 face of the other bill effective to open the closed members between which its bill points have been inserted without jamming the link upon the bills.

JOHN N. MACDONALD.
